UNITED STATES PATENT OFFICE.

DAVID BOURQUE, OF AMESBURY, MASSACHUSETTS, ASSIGNOR TO G. W. J. MURPHY COMPANY, OF AMESBURY, MASSACHUSETTS, A CORPORATION OF MASSACHUSETTS.

TURNBUTTON-FASTENER.

1,335,363.

Specification of Letters Patent. Patented Mar. 30, 1920.

Application filed March 19, 1919. Serial No. 283,575.

To all whom it may concern:

Be it known that I, DAVID BOURQUE, a citizen of the United States, and a resident of Amesbury, county of Essex, and State of Massachusetts, have invented an Improvement in Turnbutton-Fasteners, of which the following description, in connection with the accompanying drawings, is a specification, like characters on the drawings representing like parts.

This invention relates to turn button fasteners and the purpose is to provide certain improvements of construction whereby the action of such fasteners may be more reliable and uniform.

My invention will be best understood by reference to the following description of an illustrative embodiment thereof taken in connection with the accompanying drawings wherein:

Figure 1 is a side elevation of a turn button fastener of known type, but embodying my improvements;

Fig. 2 is a central vertical section; Fig. 3 is a section on the line 3—3 of Fig. 2; and

Fig. 4 is a bottom plan view of the base portion of the fastener.

Referring to the drawings, I have there shown a turn button fastener of known type adapted to be utilized with a suitable eyelet, not shown, and embodying in its construction a hollow base portion 5 pressed to form from sheet metal, the base portion having suitable provision, herein exemplified by the flange 7, for attaching it to a support and a hollow housing 9 preferably of oblong or elliptical plan, as illustrated by Figs. 3 and 4. Rotatably mounted on the base is the button or head 11 swiveled centrally thereon by means of a pin 13 passing through the opening 15 in the housing 9 and entering the head, as best shown in Fig. 2. Suitable spring means are utilized to hold the head 11 in contact with the base portion and herein I have shown a usual construction comprising a helical spring 17 within the hollow housing 9 and interposed between the inside of the outer wall thereof and the headed portion of the pin 13.

As will be well understood, when the head is in the position shown in Figs. 1 and 2, it is in alignment with the base portion 9 and permits a suitable eyelet to be placed thereover and it can then be turned into

traversing position and will overlie the sides of the eyelet and hold it in encircling relation on the base. To maintain the head in its adjusted position, the wall of the housing 9 is pressed to provide intersecting grooves 19 and 21 conveniently semi-cylindrical in form to fit the corresponding contour of the bottom part of the head 11, these grooves being separated by raised portions 23. When the head is seated in the groove 19 (Fig. 3) and it is turned to traversing position, it rides up over the separating ridges 23, compressing the spring 17, and then snaps down into the groove 21 under the influence of the spring.

Referring to Fig. 4, since the base portion 5 is made of sheet metal of practically uniform thickness, the inner surface thereof presents rounded ridges 19^a and 21^a opposite the grooves 19 and 21 at the outer side 75 and having crest portions corresponding to the deepest portions of these grooves. These ridges are separated by depressions 23^a corresponding to the exterior ridges 23.

In accordance with my invention I so form the base that the projections 23 which define the intersecting grooves 19 and 21 do not extend to the central opening 15 but terminate short thereof, and there is thus provided, encircling this opening, a flat annular zone 25 which presents interiorly, as shown in Fig. 4, a plane bearing for the terminal turn or spire of the helical spring 17. It will be understood that if the ridges 19^a and 21^a, formed at the interior of the base by the grooves at the exterior, and also the separating depressions 23^a extended to the margin of the opening, the zone immediately surrounding this portion would be undulating and if in the turning of the head 90 the spring turned somewhat on the interior of the base, it would be compressed as it rode upon one of the ridge portions. Furthermore, in the assembly of the fastener, which is customarily effected by driving the pin 13 with the spring 17 in position thereon through the opening in the base and into the head, no provision is made for positioning the end of the spring. If it were in contact with a ridge 19^a or 21^a extending to the margin of the opening, it would be compressed by the driving member much more than if it were opposite a depressed portion corresponding to one of the projecting portions 23 at the exterior of the fastener. Such a 110

fastener would be comparatively difficult to turn and might indeed stick altogether. By providing the annular zone 25 the head is properly maintained in its two adjusted positions while the tension placed upon the spring in assembly is always the same. In addition, a bearing is provided on which the spring can move freely and without any change of tension as it tends to turn when the head itself is turned. The construction provides for a uniform and satisfactorily working product and one which is, moreover, more durable since the tendency for the end of the spring to scratch and wear the comparatively thin metal of the housing 9 is eliminated.

What I claim as new and desire to secure by Letters Patent is:—

1. A turn button fastener comprising a hollow base having an opening, a rotatable head having a stem entering the opening, a

helical spring encircling the stem and having a bearing on the base adjacent the opening, the wall of the base being bent to provide intersecting grooves to receive the head in different positions, said grooves defining ridges between them, which ridges terminate outwardly of the opening whereby to provide a flat bearing for the spring.

2. A turn button fastener comprising a hollow base having a wall portion bent to provide grooves, a head swiveled on said base adapted to seat in the grooves, a spring in the hollow of the base connected to said head to seat the same, said base presenting interiorly a flat annular bearing on which the spring may turn without change of tension.

In testimony whereof I have signed my name to this specification.

DAVID BOURQUE.
